ATTORNEY

UNITED STATES PATENT OFFICE.

AUGUST R. LUSCHKA, OF CHICAGO, ILLINOIS, ASSIGNOR, BY MESNE ASSIGNMENTS, TO WILLIAM SCHEIDEL, OF CHICAGO, ILLINOIS.

ROTARY CIRCUIT-BREAKER.

SPECIFICATION forming part of Letters Patent No. 690,973, dated January 14, 1902.

Application filed August 22, 1901. Serial No. 72,870. (No model.)

To all whom it may concern:

Be it known that I, AUGUST R. LUSCHKA, a citizen of Switzerland, and a resident of Chicago, in the county of Cook and State of Illinois, have invented certain new and useful Improvements in Rotary Circuit-Breakers, of which the following is a specification.

The present invention relates to that class of rotary circuit-breakers in which a stream 10 of mercury or other like conducting fluid connected with one pole of the electromotive circuit is caused to intermittently and serially contact with a series of conducting contact-plates connected to the other pole of such elec- 15 tromotive circuit, and more especially to that particular type of circuit-breakers in which the series of contact-plates are arranged in stationary and concentric relation to a revolving turbine which is adapted to discharge a 20 radial stream of the conducting fluid against such series of contact-plates.

The object of the present improvement is to provide a simple and efficient construction and arrangement of parts with which the 25 movement of the conducting fluid is effected in a certain, simple, and positive manner and the same discharged in a constant and even stream against the series of contact-plates, all as will hereinafter more fully appear, and be 30 more particularly pointed out in the claims. I attain such objects by the construction and arrangement of parts illustrated in the accompanying drawings, in which—

Figure 1 is a central sectional elevation of 35 a rotary circuit-breaker embodying the present invention; Fig. 2, a horizontal section of the same at line A, B, Fig. 1.

Similar numerals of reference indicate like parts in both views of the drawings.

Referring to the drawings, 1 represents the 40 containing vessel or chamber, which is formed of conductive material, usually iron, and is adapted to contain a fluid body 2 of mercury or other equivalent conducting fluid.

3 is a cover of non-conducting material, 45 usually hard rubber, secured to the open top of the containing vessel 1 and forming a closure therefor.

4 and 5 are the binding-posts by which the 50 present circuit breaking or controlling apparatus is connected in circuit with the electro-

55 motive current which it is desired to break or control. In the present construction one binding-post 4 will be secured to the chamber 1, so as have conductive connection with the same and with the body of conducting fluid 2, while the other binding-post 5 is carried in an insulated manner from such containing vessel and the conducting fluid by the cover 3, as shown.

60 6 represents an annular series of spaced contact plates or segments secured to the insulating-cover 3, which series of contact-plates are conductively connected together, preferably by forming an integral portion of 65 an annular ring 7, which in turn is in conductive connection with the binding-post 5.

8 is a vertical step-bearing secured centrally in the cover 3 and adapted to support the vertically-arranged shaft 9, which extends from the exterior of the apparatus to the interior thereof and is provided with a driving-pulley 10 or other usual means by which positive rotation is imparted to such shaft in a rapid and positive manner.

75 11 is a centrifugal jet-producing head secured to the vertical shaft 9 and adapted to rotate therewith. Such jet-head will in the present invention consist of a closed horizontal top or head 12 and a circular inclined annular wall or pendent skirt 13, which ends at the bottom in a central inlet orifice or opening 14. Such jet-head is also provided with a discharge opening or orifice 15, located at one side, immediately adjacent to the intersection of the horizontal top 12 and the annular inclined wall 13.

80 16 represents a series of fixed blades secured within the containing casing 1 and adapted to prevent a circular movement of 90 the mercury or other fluid conductor during the operation of the apparatus.

In the operation of the apparatus the rapid rotation of the jet-head 11 will through centrifugal agency cause the mercury to ascend 95 the interior of the jet-head, along the inclined circular wall of the same, to be forcibly discharged in a constant stream through the jet-opening in a substantially horizontal direction. Such jet will successively contact with 100 the series of spaced contact-plates 6 to with each contact reestablish the electric circuit

through the apparatus, which had been previously broken by the passage of the jet past the space left between the respective contact-plates 6.

- 5 The usual filling of non-conducting fluid may be employed between the body of conducting fluid 2 and the cover of the apparatus to reduce sparking, as well as prevent a breaking up or flouting of the mercury.
- 10 Having thus fully described my said invention, what I claim as new, and desire to secure by Letters Patent, is—
- 15 1. In a rotary circuit-breaker, the combination of a vessel containing a conducting fluid, a centrifugal jet-head dipping into the conducting fluid and formed with a closed top, an annular wall having an inverted-cone shape truncated to form a central inlet at bottom, and a discharge-orifice formed at the
  - 20 20 point of intersection of said top and the conical wall, and a series of spaced conducting-segments arranged concentrically around the jet-head and in line with the discharge-opening of said head, substantially as set forth.
  - 25 25 2. In a rotary circuit-breaker, the combination of a vessel containing a conducting fluid, a centrifugal jet-head dipping into the conducting fluid and formed with a closed top, an annular wall having an inverted-cone
  - 30 30 shape truncated to form a central inlet at bottom, and a discharge-orifice formed at the intersection of said top and the conical wall, and a series of spaced conducting-segments forming integral parts of a circular ring, ar-
  - 35 35 ranged concentrically around the jet-head, the said contact-segments being in line with the discharge-opening of the jet-head, sub-stantially as set forth.
  - 40 40 3. In a rotary circuit-breaker, the combination of a vessel containing a conducting fluid, a cover of insulating material secured

to the top of the same, a vertical shaft journaled in said cover, a centrifugal jet-head carried by said shaft and dipping into the conducting fluid, said jet-head being formed 45 with a closed top, an annular wall having an inverted-cone shape truncated to form a central inlet at bottom, and a discharge-orifice formed at the intersection of said top and inclined wall, and a series of spaced conducting-segments forming integral parts of a circular ring attached to the insulating-cover and arranged concentrically to the jet-head, the said contact-segments being in line with the discharge-opening of the jet-head, sub- 55 stantially as set forth.

4. In a rotary circuit-breaker, the combination of a vessel containing a conducting fluid, a cover of insulating material secured to the top of the same, a vertical shaft journaled in said cover, a centrifugal jet-head carried by said shaft and dipping into the conducting fluid, said jet-head being formed with a closed top, an annular wall having an inverted-cone shape truncated to form a central inlet at bottom, and a discharge-orifice formed at the intersection of said top and the conical wall, a series of spaced conducting-segments forming integral parts of a circular ring attached to the insulating-cover and arranged concentrically to the jet-head, and a series of stationary blades secured in the bottom of the containing-chamber and adapted to prevent a circular movement of the conducting fluid, substantially as set forth. 75

Signed at Chicago, Illinois, this 20th day of August, 1901.

AUGUST R. LUSCHKA.
